[57] ABSTRACT

A fusible plug assembly adapted for use with projectiles, boilers and other apparatus which for safety purposes requires thermally responsive means for pressure release or to prevent undesired pressure buildup. The disclosed embodiment is a fusible lifting plug assembly for use in transportation and storage of ordnance projectiles and includes a fusible plug of a bismuth alloy and an insert molded in said plug to conserve the amount of the bismuth alloy that is required without altering the normal functioning of the fusible plug.

FUSIBLE PLUG

BACKGROUND OF THE INVENTION

The present invention relates to a fusible plug assembly that is thermally responsive to ambient temperature to provide a vent opening to a chamber or other device if the ambient temperature becomes excessive.

It is conventional practice to provide fusible plug assemblies for safety purposes in which the plug has a fusible core of a bismuth alloy. The main component of these alloys normally is bismuth, and the alloys are known to have very low melting temperatures and low physical strength. As such they have been used in safety devices associated with sprinkler systems, compressed gas tanks, fire alarm devices, disarmed ordnance projectiles, and the like.

As a general rule, bismuth alloys of approximately 50 percent bismuth exhibit little change of volume during solidification, and alloys containing more than this amount expand while those containing less tend to shrink during solidification. Thus when used as the fusible material in a lifting plug for a disarmed ordnance projectile an alloy having bismuth in excess of 50 percent is desired, and a very suitable alloy is one which contains approximately 52.5 percent bismuth, 32 percent lead and 15.5 percent tin. Lifting plugs of this character are formed by pouring molten alloy into a bore extending axially through the body of the plug and when the alloy solidifies it expands to provide a rigid seal in the bore. The alloy will melt at a temperature near 210° F to provide a vent opening for a projectile in which the lifting plug is secured if the projectile is subjected to undesired heating.

In conventional lifting plugs of the type described, approximately one-tenth of a pound of the alloy is required for each fusible lifting plug. This may appear to be a relatively small amount, but it represents a significant amount of bismuth when the aggregate numbers of projectiles that are produced are considered. Bismuth is in limited supply and its cost per pound is relatively high. Thus, there is a need for an improved fusible plug which will perform to the same standards as conventional units produced heretofore, but which will utilize substantially less bismuth.

SUMMARY OF THE INVENTION

The present invention has overcome inadequacies of fusible plugs as heretofore known and provides an improved construction whereby the quantity of bismuth required can be reduced materially without reducing the effectiveness of the plug. This has been accomplished by including an insert within the bore of the plug which is operable to displace approximately one-half of the bismuth required in each plug, and which has a configuration so that it will not become an obstruction in the bore if the bismuth alloy melts.

According to one form of the present invention, a fusible plug assembly is provided that is thermally responsive to ambient temperature so that a portion thereof will melt to provide a vent opening when a preselected temperature is reached. The assembly comprises the plug having a cylindrical bore defining a through passageway, an insert position in the bore and having around its periphery a radially outwardly directed groove facing the inner wall of the bore, and fusible material in the bore and said groove sealing closed the bore and adapted to fuse at the preselected

temperature to permit the material to flow from the bore and to allow the insert to pass freely through the bore. The insert has an external configuration so that its outermost surfaces conform to the shape of a sphere that has a radius smaller than the radius of the bore. By virtue of this construction and arrangement, the insert cannot become caught or otherwise block the passageway after the fusible material has been melted.

To assure that a proper seal is provided during the molding of the fusible material in the plug, it is found desirable to use a bismuth alloy containing 52.5 percent bismuth, 32 percent lead and 15.5 percent tin. This alloy has the properties of expanding when it solidifies, and it has a melting point in the range of 210° F which is sufficiently low to function as a fusible material for safety devices. The insert that is molded within the fusible material is capable of displacing at least half of the bismuth alloy that normally would be used in the prior art devices, and, therefore, it serves to reduce by approximately one-half the quantity of bismuth that is required.

Thus, it is an object of the present invention to provide an improved fusible plug assembly that will meet all the standards of performance required by prior art devices, but which will reduce substantially the quantity and cost of the fusible material that is required in the plug.

Other objects of this invention will appear in the following description and appended claims, reference being had to the accompanying drawings forming a part of this specification wherein like reference characters designate corresponding parts in the several views.

BRIEF DESCRIPTION OF THE DRAWING

FIG. 1 is a side elevational view of a fusible plug assembly embodying one form of the present invention; FIG. 2 is a top plan view of the fusible plug assembly; FIG. 3 is a longitudinal section taken on the lines 3-3 of FIG. 1; FIGS. 4, 5, and 6 illustrate modified forms of the insert that can be used in the fusible plug assembly.

DESCRIPTION OF THE PREFERRED EMBODIMENTS

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring not to the drawing, the invention will be described in greater detail. The fusible plug assembly 10 includes the plug 12, the insert 14, and the fusible material 16.

The plug 12 in the illustrated embodiment is a metal casting, preferably of malleable iron or steel, which has a cylindrical bore 18 that extends axially through the body portion 20 to define a through passageway. The body portion is also externally threaded, as at 22, so that it can be secured in the end of a disarmed ordnance projectile. The plug 12 also includes the eyelet 24 which is integrally formed with the cylindrical body portion 20 for lifting the ordnance projectile.

The insert 14 has an exterior surface 26 which conforms to the shape of a sphere which has a radius

smaller than the radius of the bore. The insert 14 also has an annular groove 28 that is radially outwardly directed so that it faces the inner wall of the bore 18.

The fusible material fills the groove 28 and is firmly in engagement with the inner wall of the bore 18 so that it provides a rigid seal within the bore 18. In the illustrated embodiment of the invention the fusible material 16 is a bismuth alloy having more than 50 percent bismuth so that when the molten material solidifies during formation of the fusible plug assembly, it will expand to assure that a rigid seal is provided in the bore 18. A preferred bismuth alloy which provides a desired melting point temperature and which utilizes a minimum amount of bismuth while still providing the desired expansion during solidification is one which contains 52.5 percent bismuth, 32 percent lead, and 15.5 percent tin. The fusible plug assembly can readily be formed by placing the plug 12 in a mold, positioning the insert 14 in an appropriate position within the mold and then pouring the molten fusible material 16 into the cavity defined by the mold apparatus, the insert 14, and the bore of the plug 12. This fusible material has a melting point of approximately 210° F so that in the event overheating of the disarmed ordnance projectile should occur, the fusible material 16 will melt at that temperature, and melted material and the insert 14 will then freely flow or fall from the bore 18 to permit venting of the disarmed ordnance projectile so that it will not be detonated.

FIGS. 4, 5, and 6 show other forms of inserts 30, 32, and 34 which may be used in place of the insert 14 illustrated in FIG. 3. It will be observed that each of these modified forms of inserts have exterior surfaces which conform to the shape of a sphere so that they will pass freely through the bore 18 should the fusible mate-

rial melt. These inserts also have grooves 36, 38, and 40 in which the fusible material can flow into during the molding operation and from which they can radially expand during solidification to seal rigidly the bore 18.

It is claimed:

1. A fusible plug assembly that is thermally responsive to ambient temperature so that a portion thereof will melt to provide a vent opening when a preselected temperature is reached, said assembly comprising a plug including a portion having a cylindrical bore defining a through passageway of uniform diameter throughout its length, an insert positioned in said bore and having around its periphery a radially outwardly directed groove facing the inner wall of said bore, and fusible material in said groove and extending into said bore in sealing relationship therewith, said material adapted to fuse at said preselected temperature to permit said insert to pass through said bore, said insert being contoured so that its outermost surfaces conform to the shape of a sphere that has a radius smaller than the radius of said bore so that when said material fuses the insert can pass freely out of either end of said passageway.

2. The fusible plug assembly that is defined in claim 1, wherein said fusible material is a bismuth alloy containing more than 50 percent bismuth.

3. The fusible plug assembly that is defined in claim 2, wherein said alloy contains approximately 52.5 percent bismuth, 32 percent lead and 15.5 percent tin.

4. The fusible plug assembly that is defined in claim 1 which includes a cylindrical body portion that is externally threaded at one end and through which said bore extends, and an eyelet integrally connected to the other end of the body portion.
